UNITED STATES PATENT OFFICE.

SIDNEY BOWDIDGE, OF BROOKLINE, MASSACHUSETTS.

FUNNEL.

1,088,649.

Specification of Letters Patent.

Patented Feb. 24, 1914.

Application filed June 9, 1913. Serial No. 772,482.

To all whom it may concern:

Be it known that I, SIDNEY BOWDIDGE, a citizen of the United States, and resident of Brookline, in the county of Norfolk and 5 State of Massachusetts, have invented new and useful Improvements in Funnels, of which the following is a specification.

This invention relates to a combined spout and funnel for fluids, and while susceptible 10 of more general use, is particularly adapted to spouts for attachment to funnels used for pouring fluids into bottles and other receptacles having small necks.

In the accompanying drawings which 15 illustrate one embodiment of the invention,—Figure 1 is a sectional view of a combined funnel and spout containing the invention, showing the spout attached to a funnel and inserted in the neck of a bottle; 20 Fig. 2 is a side view of the spout; Fig. 3 is a section on line 3—3 of Fig. 1; and Fig. 4 is a bottom view of the spout.

The device, as herein shown, comprises a tubular body *a*, having at its top a relatively 25 large hub *b*, with the ledge or shoulder *c* therebetween. In order to support the spout in receiving apertures of varying sizes, such as bottle necks of different sizes, the spout is provided with external supporting members 30 converging from their upper ends downward, to engage the inner periphery of the bottle neck *B* or other aperture. As herein shown said supporting members consist of three radially disposed tapering vanes *d* extending from the top of the hub downward to, and merging with, the surface of the tubular body *a*. These vanes will support 35 the spout in a throat *B* of any size from the diameter of the tubular body *a* to the maximum diameter at the top of said vanes, and will also provide spaces for the escape of air between the body of the spout and the walls of the aperture through the neck *B*.

Within the hub *b* is a strainer *e*, having 45 spacers or legs *f* on its under side which engage shoulder *c* and support the strainer in a position spaced apart from said shoulder, thereby leaving a clear space between the strainer and the entrance to tube *a*. By this 50 arrangement a sufficient volume of fluid is permitted to pass through the strainer into the chamber between the strainer and the entrance to tube *a* to insure a solid or unbroken stream to issue from tube *a*, instead 55 of a broken stream as would result if the strainer rested directly on the shoulder *c*

and across the entrance to tube *a*. Said strainer is made removable for the purpose of cleaning or repairing the parts.

The hub *b* is interiorly threaded so that it 60 may be detachably and interchangeably secured to the outlet end of a funnel *F*, or other conveyer for the fluid, which is to be passed through the spout. The strainer is clamped between the end of the funnel and 65 shoulder *c*. Thus it will be seen that the hub *b* in conjunction with the threaded end of the funnel *F* performs not only the functions of a coupling for separably uniting the funnel *F* and the tube *a*, but at the same 70 time operates separably to clamp the strainer in place, and serves as a housing for the removable strainer, which requires no other fastening devices than said coupling members. Furthermore, by locating the strainer 75 in the enlarged hub, the funnel is left open and free from strainer-supporting fittings or other obstructions difficult to clean and liable to damage through accident, while at the same time the strainer may be sufficiently 80 spaced from the shoulder of the hub as above described to admit of the free passage of the fluid.

With the above described construction a device is provided wholly separable or dismountable, the interior surfaces of both funnel and tube members when separated being readily accessible and free from strainer supporting brackets, or vortex interrupters, which would interfere with the 90 convenient and thorough cleaning of the parts.

In order to interrupt and destroy the vortex which tends to form in the fluid passing through the funnel, and so further safeguard 95 the even flow of the fluid and the unbroken stream in the spout, a vortex interrupter is provided, consisting, as herein shown, of a T-shaped projection *g* secured to the upper side of the strainer *e*, and extending upward 100 far enough to enter well into the delivery end of the funnel *F* where the vortex tends to form. The cross bar at the top of this T-shaped projection effectually prevents the forming of a vortex in the passing fluid, and 105 the T also performs the office of a handle by which the strainer may be removed or inserted.

Although the device is shown as secured 110 to a funnel, it will be understood that this is merely for the purpose of illustration, and that it may be used in conjunction with any

suitable form of fluid conveyer as well as a funnel; also that the supporting vanes will perform their functions in connection with various other sorts of receiving apertures as well as with the throat of a bottle.

I claim:

1. A spout comprising a tubular body, a relatively large hub at its top, and a shoulder therebetween, a funnel connected to said hub, a removable strainer in said hub, and a vortex interrupter extending upward from the top of said strainer and forming a unitary part thereof so as to serve also as a handle to remove said strainer.
- 15 2. A spout comprising a tubular body, a relatively large hub at its top, and a shoulder therebetween, a funnel connected to said hub, a removable strainer in said hub, and a T-shaped vortex interrupter secured to the top of said strainer, and forming a unitary part thereof so as to serve also as a handle to remove said strainer.
- 20 3. In combination, a spout comprising a tubular body, a relatively large interiorly screw-threaded hub at the top, and a

shoulder between said hub and tubular body, a funnel screwed into said hub, a removable strainer in said hub clamped in place between the end of said funnel and said shoulder, and a vortex interrupter extending from the top of said strainer into the end of said funnel.

30 4. In combination, a spout comprising a tubular body, a relatively large interiorly screw-threaded hub at the top, and a shoulder between said hub and tubular body, a funnel screwed into said hub, a removable strainer in said hub clamped in place between the end of said funnel and said shoulder, spacers carried by said strainer to hold the same out of engagement with said shoulder, and a vortex interrupter extending from the top of said strainer into the end of said funnel.

35 Signed by me at Boston, Massachusetts, this 2nd day of June, 1913.

40 SIDNEY BOWDIDGE.
